UNITED STATES PATENT OFFICE.

GEORGE S. MARTIN AND MAX BERGER, OF ANDERSON, INDIANA.

BRUSH.

1,099,262.

Specification of Letters Patent. Patented June 9, 1914.

Application filed September 24, 1913. Serial No. 791,535.

To all whom it may concern:

Be it known that we, GEORGE S. MARTIN and MAX BERGER, citizens of the United States, residing at Anderson, in the county of Madison and State of Indiana, have invented certain new and useful Improvements in Brushes, of which the following is a specification.

The brush which is the subject matter of the present application for patent is designed more particularly to be used for cleaning the type of typewriters, letter presses, or other writing and printing machines, as well as printers' forms, and its object is to provide a brush by which the cleaning of the type can be done easily and thoroughly, without loss of time and with a considerable saving of labor. This object is attained by means of a novel combination and arrangement of parts to be hereinafter described and claimed, reference being had to the accompanying drawing, in which—

Figure 1 is a side elevation of the brush; Fig. 2 is a longitudinal section on the line 2—2 of Fig. 1, and Fig. 3 is a cross-section on the line 3—3 of Fig. 1.

Referring specifically to the drawing, 5 denotes the head of a brush having bristles 6 and 7, respectively, on opposite sides, a 10 double brush thus being had. The head has a central longitudinal passage 8 extending thereto from the rear end of the head and terminating short of the forward end thereof. From one side of this passage 15 minute orifices 9 lead through the head to that side thereof carrying the bristles 6 and open through said side. A cleansing fluid, such as gasolene, is adapted to be discharged through the orifices onto the bristles 6, this 20 part of the brush therefore forming a fountain brush.

The device is provided with a hollow, cylindrical handle 10 carrying at its outer end a cap 11 which is screwed on and is thus 25 readily removable from the handle. The cap has an externally screw-threaded nipple 12 which is screwed into the outer end of the passage 8, whereby a separable connection between the cap and the brush head 5 is 30 had.

The outer end of the nipple 12 forms a seat for a valve 13 having a stem 14 which passes lengthwise through the nipple and into the cap 11. A spring 15 holds the valve nor- 35 mally seated, said spring being coiled around the valve stem 14 between an annular shoul-

der 16 in the cap and a cross-pin 17 on the valve stem.

The handle 10 carries a rod 18 for operating the valve 13. This rod extends centrally and lengthwise through the handle, from the butt end of which it projects and is fitted thereat with a push button 19. In the hollow of the handle 10 is a spider 20 which supports the forward end of the rod, and between this spider and a cross-pin 21 on the rod, a spring 22 is coiled around the latter, which serves to normally hold the rod retracted. The rod is in line with the valve stem 14, and when pushed forward it pushes 70 against the inner end of the valve stem and unseats the valve 13. The rod is operated, to open the valve, by pressing on the button 19, and upon removing the pressure the spring 22 retracts the rod and allows the 75 spring 15 to close the valve.

The handle 10 is hollow in order that it may serve as a container for the gasolene or other cleansing fluid, the same being discharged onto the bristles 6 when the valve 80 13 is opened, the fluid thereupon discharging into the passage 8 and flowing through the orifices 9 to the bristles 6.

The rear or butt end of the handle 10 is closed by a plug 23 having a central air port 85 24, through which the rod 18 passes. The rod carries a valve 25 which seats over the air port when the rod is in retracted position, to prevent leakage of the cleansing fluid from the butt end of the handle. When 90 the rod is pushed in to open the valve 13, the valve 25 is unseated and air is allowed to enter the hollow of the handle containing the supply of cleansing fluid, and the latter is freely discharged. The cap 11 is remov- 95 able from the handle 10, as hereinbefore described, in order to permit the latter to be filled with the cleansing fluid.

In use, the fountain brush formed by the bristles 6 is first employed to remove all 100 accumulations on the type, after which the type is brushed with the bristles 7, which latter remain dry. By this operation, the type can be quickly and thoroughly cleaned. The removal of the cap 11 does not disturb 105 the valve 13 as the valve stem 14 and the rod 18 are separate.

We claim:

A brush comprising a head carrying bristles and having a passage leading from 110 one end of the head, with orifices leading from the passage to the bristles, a hollow

handle, a cap connected removably to one end of the handle, and to the aforesaid passage, a valve carried by the cap and having a stem, a valve-operating rod carried by the handle and engageable with the valve stem, said rod and valve stem being separate, a plug closing the outer end of the handle, said plug having an air port through which the rod passes, and a valve carried by the 10 rod and seating over the air port when the

rod is in retracted position, and uncovering the air port when the rod is advanced to open the first-mentioned valve.

In testimony whereof we affix our signatures in presence of two witnesses.

GEORGE S. MARTIN.
MAX BERGER.
